[57] CLAIM

The ornamental design for a rechargeable fluorescent lantern, as shown and described.

DESCRIPTION

FIG. 1 is a front elevational view of a rechargeable fluorescent lantern showing my new design.

FIG. 2 is a top plan view thereof;

FIG. 3 is a bottom plan view thereof;

FIG. 4 is a right side elevational view thereof, the left side being a mirror image;

FIG. 5 is a right side elevational view thereof with the adjustable rear stand and the recharging plug in the extended position, the left side being a mirror image;

FIG. 6 is a rear elevational view thereof with the stand and plug in the closed position; and

FIG. 7 is a top plan view thereof with the stand and plug in the extended position.
